UNITED STATES PATENT OFFICE.

JOHN E. BELL, OF BROOKLYN, NEW YORK, ASSIGNOR TO FOSTER WHEELER CORPORATION, OF NEW YORK, N. Y., A CORPORATION OF NEW YORK.

FLUID HEATING.

Application filed July 17, 1924. Serial No. 726,584.

My present invention relates to fluid heating apparatus, such as a steam superheater which is incorporated in a combustion chamber furnace wall or is otherwise exposed at 5 one side to a source of radiant heat at high temperature, and is concerned with the mechanical construction and arrangement of such apparatus, and in particular with the provisions made for accommodating or restraining the tendency of the apparatus to change its form and dimensions as a result 10 of its thermal expansion and contraction.

The invention was primarily designed and is especially adapted for use in connection 15 with steam superheaters composed of elements each formed of one or more sections with each section several feet in length and having its walls substantially thicker than ordinary steam pipes having the same cross 20 sectional area for steam flow. These sections may well be formed of cast steel, and in such case are ordinarily rectangular in cross section with the outline of the element and of the steam channel therein, each elongated 25 in transverse section in a direction parallel to the heat absorbing surface of the element.

When such an element is put into use, the inner side of the section adjacent the source 30 of radiant heat is heated to a temperature appreciably above that of the opposite or outer side of the element, and the sides of the element transverse to the heat absorbing surface are hotter at their edges adjacent the heat absorbing face than at their 35 opposite edges. If the temperature in the element varied progressively and uniformly from the heat absorbing face of the element to its opposite side, the element, if straight when cold, would simply bend into the form 40 of an arc with the convex side toward the furnace chamber when heated up if free to so bend, and when cooled down would return to its original shape. In such case the changes in temperature would not subject 45 the element to stress if the latter were free to bend and straighten out in the manner described.

In practice, however, this uniform graduation in the temperature of the metal of the 50 element does not exist. The side of the element remote from the heat absorbing face will be cooler adjacent the steam channel than at its face remote from the steam channel owing to the cooling action of the 55 steam and the fact that the heat which that

side supplies to the steam is received wholly or mainly by conduction through the portions of the element which are transverse to the heat absorbing face. In consequence, when the element is put into the service and 60 thereby heated up, the element tends to bend into the form of an arc with its convex side toward the source of radiant heat, but this bending sets up internal stresses which tend to compress the material in the portion of 65 the element adjacent the source of radiant heat and to stretch portions of the element more remote from the source of radiant heat. In the practical use of radiant heat superheaters, the temperature to which the hotter 70 portion of the element is subjected is a good annealing temperature, while the temperature of the portion of the element more remote from the source of radiant heat is below the annealing temperature. In conse- 75 quence, when the hotter side of the element is subjected to a compression stress it yields more or less to this stress and takes a permanent set. When thereafter the element cools down, it does not tend to return to its 80 original straight form, but to bend into the form of an arc having its concave side toward the source of radiant heat. To some extent this change in form is cumulative 85 with successive heating up and cooling off of the element, and the latter will eventually acquire a permanent curvature when cold with its concave side toward the furnace.

Where the elements are comparatively short, say 4, 5, or 6 feet in length, this ultimate curvature is not ordinarily sufficient to be particularly objectionable, and I have found that such elements may well be so mounted that they are free to make the changes in form which the changes in temperature tend to produce. With elements of greater length however, the distortion in the assembled structures which the temperature changes in the elements tend to produce is objectionable and should be restricted or prevented. To this end, I mount the elements in a supporting structure adapted to permit the bodily elongation and contraction of the elements, but effective to limit the otherwise substantial bending movements of 100 the elements as they are heated and cooled. Advantageously in many cases, the supporting framework or structure and the elements are assembled to form a self-contained unit 105 which can be mounted in a furnace wall and 110

which will absorb the stresses due to changes in temperature without transmitting any portion thereof to the other portions of the furnace wall. The tendency of a metal such as cast steel to elongate and contract in response to changes in its temperature is not uncommonly regarded as a practically irresistible force. I have found however, that with cast steel elements such as are now being employed in radiant heat superheaters, the tendency of the element to bow into arc form as the result of the temperature changes to which it is subjected, amounts only to something like 400 pounds per foot of length of the element, and that it is entirely feasible in practice to prevent objectionable bowing of the elements by attaching them to a framework, having the necessary strength.

The various features of novelty which characterize my invention are pointed out with particularity in the claims annexed to and forming a part of this specification. For a better understanding of the invention, however, its advantages and specific objects obtained with its use, reference should be had to the accompanying drawings and descriptive matter, in which I have illustrated and described some of the various forms of construction which may be employed in accordance with the present invention.

Of the drawings:

Fig. 1 is an elevation partly in section, of a portion of the wall of the combustion chamber of a boiler furnace incorporating a radiant heat superheater;

Fig. 2 is a vertical section taken on the line 2—2 of Fig. 1;

Fig. 3 is a plan view partly in section on the line 3—3 of Fig. 1;

Fig. 4 is an elevation taken similarly to Fig. 1, illustrating a modified construction;

Fig. 5 is a section on the line 5—5 of Fig. 4;

Fig. 6 is a section on the line 6—6 of Fig. 4;

Fig. 7 is an elevation of a portion of the outer side of still another form of combustion chamber furnace wall superheater;

Fig. 8 is a section on the line 8—8 of Fig. 7;

Fig. 9 is a section on the line 9—9 of Fig. 7;

Fig. 10 is a partial elevation of a furnace wall superheater, comprising short elements allowed freedom to bend;

Fig. 11 is a section on the line 11—11 of Fig. 10; and

Fig. 12 is an elevation of a portion of the outer side of the furnace wall shown in Figs. 10 and 11.

In the drawings, and referring first to the construction shown in Figs. 1, 2, and 3. A represents the housing wall of a boiler furnace, at the rear of the combustion chamber a, which is beneath the boiler water tubes

B. Incorporated in the wall A and forming a part thereof, is a radiant heat superheater composed of cast steel elements C, rectangular in cross section, as shown in Fig. 3. Each element C is connected at its ends through transverse and more or less flexible pipe connections D to the steam inlet and outlet headers E and E', and each element C is anchored at its center by a suitable connection to a horizontal I beam F. In the particular construction shown, wherein the superheater extends the full width of a boiler furnace of large size, the superheater is in effect divided into two sections, with an I beam F for each section the two I beams F being arranged end to end and each connected at its end adjacent the other to a common vertical I beam G. At its end remote from the I beam G, each I beam F is connected to a vertical channel bar H. Each channel bar H is connected at its upper and lower ends to the upper and lower ends of the I beam G by channel bars I. The members F, G, H, and I form the main members of a supporting framework for the superheater which is strong enough and rigid enough to hold the superheater elements C against flexure when connected to the latter, as hereinafter described, and which is adapted to be incorporated in the furnace housing wall and carry the weight of the portion thereof above the superheater.

To connect each element C to the I beam F at its rear a yoke-like part C' is welded or otherwise rigidly secured to the rear side of the element. The yoke-like part C' straddles, and is connected by a through pin J' to the tongue J formed by the adjacent flanges of oppositely facing angle bars riveted to the I beam F. To compensate for nonuniformity in relative proportions of the various elements C and yokes C' and facilitate assembly, the space in the parts C' is of a width greater than the thickness of the tongue J so that by means of washers J² on each pin J' (shown better in Fig. 6), the corresponding element C may be vertically adjusted.

At each end each element C is connected to the corresponding channel beam I by provisions which do not interfere with the longitudinal expansion and contraction of the element but do prevent movement of the element toward and away from the I beam I. These provisions as shown comprise a tongue-like projection C² welded or otherwise secured to the end of the element C and a vertical pin K' by which the tongue C² is connected to the side walls of a channel bar K, the base of which is secured against the adjacent flange of the I beam I. Advantageously and as shown, the channel bars K are formed of cast steel and are each of a length equal to the width of some three or four of the elements C. The space be-

tween the parallel flanges of the channel bars K is sufficiently greater than the thickness of the tongue projection C² to permit the latter to slide along the pin K' as required 5 to accommodate the bodily longitudinal expansion and contraction of the elements C.

In the preferred construction shown, the space between the elements C and the inner edges of the frame members F, G, H, and I 10 is packed with a suitable heat insulating and gas leakage preventing material as Sil-o-Cel, and this material is held in place by cover plates L secured to the members H, J and K.

The bottom horizontal frame members I 15 may rest directly upon the subjacent masonry portion of the wall A, but, on account of the necessity for providing for the longitudinal contraction and expansion of the elements C and the consequent up and down 20 movement of the end connections, D, I mount the members I, in the construction shown in Figs. 1, 2, and 3, on cast metal pedestals M incorporated in the housing wall, and provide a space between the sub- 25 jacent brickwork portion of the housing wall into which the upper ends of the pedestals M extend and through which the lower end connections D pass. This space is advantageously filled with Sil-o-Cel or analogous 30 heat insulating and gas leakage preventing material, which will yield to permit of the movements of the pipe connections D as the elements C expand and contract. As shown, the outer end of this space is closed by a 35 cover plate O formed in sections and apertured to receive one or two pipes D. The sections of the cover plate O are held against the outer edge of the Sil-o-Cel filled space by angle bars O' between which the pipe 40 connections D are clamped. As shown, the angle bars O' are formed in short sections and each engages some two or three of the pipes D.

At the upper end of the superheater, a 45 space is provided between the upper channel beam I and the brickwork of the boiler housing wall above the superheater through which the upper pipe connections D pass, and in which they are surrounded by Sil-o- 50 Cel or the like as at the bottom of the superheater. For this purpose, cast steel elements in the form of I bars P are mounted on the top of the upper beams I and support sectional cast steel cover plates P' on 55 which the brickwork above the superheater is supported. The outer edge of this space is closed by parts O and O', similar to those employed at the bottom of the superheater.

The flexibility of the pipe connections D 60 may be sufficient to accommodate the longitudinal expansion and contraction of the element C when the headers E and E' are rigidly mounted. Advantageously, in some cases, however, the headers E and E' may be 65 yieldingly supported to reduce the bending

stress on the pipe connections D. This yielding support is provided in Figs. 1, 2, and 3 by the springs Q, resting on brackets Q' secured to the boiler housing buckstays Q² and engaged at their upper ends by nuts on 70 the ends of yoke members Q³ by which the headers E and E' are suspended from the brackets Q'.

With the described construction, it will be apparent that the elements C may elongate and shorten as their temperatures increase and decrease without putting objectionable stress on any portion of the apparatus, but their tendency to bow in planes parallel to their length and transverse to 80 their heat absorbing surfaces will be prevented by the superheater supporting framework if the latter is strong enough as it may well be to withstand the tendency of 85 the elements to bow. The maintenance of a smooth and comparatively flat heat absorbing superheater face is especially desirable to insure the effective operation of the soot blowing provisions C⁵⁰ provided for sweeping 90 the face of the superheater with jets of steam or other cleaning fluid in order to remove the deposited furnace dust. The superheater as a whole forms a self-contained unit which is incorporated in the 95 boiler furnace housing and the stresses set 100 up in different portions of the superheater structure, and such relative movement of the parts thereof as are permitted, in response to the changes in temperature to which the superheater is subjected, do not react upon or disturb the masonry portions of the boiler housing.

In Figs. 4, 5, and 6 I have illustrated a construction which is essentially the same in its general features as that shown in Figs. 1, 2, and 3, except as to certain specific differences resulting from the fact that the superheater elements C are horizontally disposed in Figs. 4, 5, and 6. In consequence, the beams FA and IA of Figs. 4, 5, and 6 110 which correspond to the beams F and I of the construction first described, are vertical and are connected at their upper and lower ends by two horizontal channel beams HA. The connections between the elements C and the beams FA and IA are similar to those 115 between the elements C and the beams F and I in the construction first described. In Figs. 4, 5, and 6, the tendency of the elements to rotate under the action of gravity about the pins K' and J' is resisted by the 120 end connections D which for this purpose are supported adjacent the elements C by sectional supporting members R formed with horizontally elongated slots R' to permit the bodily elongation and contraction of 125 the elements C. As shown, the plates R are carried by vertical channel beams IB alongside the channel beams IA and separated from the latter by a space, which may be 130

filled with Sil-o-Cel to provide a gas tight and heat insulating packing about the end connections D, the outer edges of these spaces being closed by cover plates O' and angle bars O as in the construction first described. In Figs. 4, 5, and 6 the headers E, which are vertical, are rigidly supported from the housing buckstays Q² by clamping them to cross beams Q⁴ which are bolted to the buckstays.

In the construction illustrated in Figs. 4, 5, and 6, the elements C are arranged in two horizontal banks, the two banks being separated by refractory materials which may be supported on the upper element in the lower bank. The possibility of thus holding refractory material incorporated in the heat absorbing face of the superheater is an advantageous one, as it is sometimes desirable to thus reduce the amount of heat absorbing surface of the superheater without correspondingly reducing the extent of area of the boiler furnace wall formed by the superheater as a whole.

The principal formal differences between the construction shown in Figs. 7, 8, and 9 and the constructions in Figs. 1 to 6 arises from the fact that in Figs. 7, 8, and 9, the main elements of the supporting framework for the superheater are formed by a multiplicity of I beams GB which are parallel to the superheater, the elements C of which are vertical. The I beams GB are connected at their ends by channel beams IB.

The intermediate beams GB as shown are arranged in adjacent pairs with the two beams of each pair spaced away from one another a small distance and the adjacent beams of adjacent pairs spaced away from one another by a greater distance. The adjacent beams of adjacent pairs are connected by short horizontal beams FB and brackets FB¹⁰ about midway between the top and bottom ends of the elements C. The two beams of each pair are also connected by horizontal webs FB¹¹ and brackets FB¹⁰.

In this construction the elements C are formed in two sections of approximately the same length which are connected end to end by an internal threaded nipple C¹⁰ and also by welding the adjacent ends of the sections together. Each element C is anchored adjacent its center by two connections one to each end of each of the two sections of the elements. The connections for the upper sections comprise rivets or bolts for securing lugs C¹¹ welded to the sections to the vertical flange of an angle bar FC having its horizontal flange riveted to the horizontal flange of a second angle bar FD, the latter having its vertical flange riveted to the beams GB. Similarly the lugs C¹¹ at the top of each lower section element are attached to the vertical flange of an angle bar FC having its horizontal flange riveted to

the horizontal flange of an angle bar FD which has its vertical flange riveted to the beams GB and to the transverse beams FB. With this arrangement, the anchorages for the lower ends of the upper sections of the elements C are sufficiently flexible to accommodate the elongation and contraction of the portion of each element between its two central anchorages FC.

Each element C is provided adjacent its upper end with a supporting lug C¹¹ to which is secured a bolt passing through an opening F¹⁵ in the vertical flange of an angle bar FE having its horizontal flange riveted to the horizontal flange of an angle bar FF which in turn is riveted to the beams GB. Each element C is similarly connected at its lower end by angle bars FE and FF to the beams GB. The openings F¹⁵ in the angle bars FE for the bolts carried by the lugs C¹¹ are larger than the bolts to accommodate the elongation of the expansion and contraction of the elements C, and are also enlarged horizontally to compensate for irregularities in the shape and proportions of parts and thereby facilitate assemblage. The bolt or rivet holes F¹⁶ in the angle bars FC may be similarly elongated for the same purpose as shown. As shown in Fig. 8 the wall in which the superheater is incorporated forms the rear wall of a combustion chamber which extends under the front portions only of the water tubes and which supports the lower edge of a baffle extending across the water tubes. This baffle is supported on hollow box-like parts PA of cast metal through which the upper end connections D pass loosely. The space within the boxes PA around the end connections D, are packed with Sil-o-Cel or the like, the outer ends of these spaces being practically closed by the superheater header E which in this construction is connected to the elements C by rather short pipe connections D. The lower end connections D pass through cover plates O which overlap the casing plates L and LA between the elements C and their supporting framework.

In Figs. 10, 11, and 12 I illustrate a construction in which the superheater elements C are comparatively short and are permitted to bow as well as to elongate and contract in response to the temperature changes to which they are subjected. In the particular form illustrated in Figs. 10, 11, and 12 the superheater is incorporated in the bridge wall AA forming the rear wall of the combustion chamber proper of a boiler furnace in which the combustion chamber underlies the front portions only of the boiler tubes B with a baffle B¹⁰ extending across the bank of tubes and resting on the upper edge of the bridge wall. It will be understood, however, that the described construction is not limited to use in the type of boiler re-

ferred to, but may be used in the outer wall extends the full width of a combustion chamber of the combustion chamber underlying the entire bank of water tubes.

- In Figs. 10, 11, and 12 the lower ends of 5 the elements C rest on the portion of the bridge wall beneath them, and the lower transverse pipe connections D are restrained against substantial flexure by supporting means which comprises a sleeve U for each 10 lower end connection D through which the latter passes. Each sleeve U is expanded at its ends into openings formed for the purpose in the inner and outer sides of cast iron parts T in the form of boxes open at 15 their tops and each of such length, measured parallel to the length of the bridge wall as to accommodate a plurality (five as shown) end connections D. The box-like castings T may be strengthened by internal ribs or 20 webs T'. The parts T rest on cast metal supports W in the form of channel bars, and the supports W and parts T are bedded in suitable cement on the subjacent portion 25 of the bridge wall AA proper. The spaces in the parts T surrounding the sleeve D may be surrounded by ganister A⁹ or the like, which forms a support for the masonry portion A¹⁰ of the bridge wall AA back of the 30 elements C.
- The wall portion A¹⁰ supports at its top, provisions analogous in character to those illustrated in Figs. 1, 2, and 3, and 7, 8, and 9 for permitting the upper end connections D to bend in response to the changes in 35 form and length of the superheater elements as their temperatures vary. The provisions shown for this purpose comprise similar castings X and XA having flat top and bottom portions and vertical web portions X', 40 providing open ended channels one for the upper end connection D, the inner end of each of which is received in a corresponding channel of a member XA while an outer portion is received in a channel in a member X. The castings X and XA are shown 45 as resting on cast supports WA having flanges at their under sides and bedded in a suitable cement on the top of the wall portion A¹⁰. Cast metal cover plates Y on the 50 tops of the parts X and XA close the joints between the latter and directly support tiles A¹¹ on which the baffle B¹ rests. The spaces about the end connections D within the rear members XA and between those members and 55 the outer members X are packed with Sil-o-Cel or the like. The upper end connections D are connected into a header EA which is divided into inlet and outlet portions E⁶ and E⁷ respectively, by a central diaphragm E⁵. 60 The lower end connections D are connected into a header EB closed at each end. This arrangement of headers is desirable in some cases as in the particular construction illustrated in which the superheater is composed 65 of elements which are five feet or so long and
- With the construction shown in Figs. 10, 11, and 12, the upper end of each element C is free to rise and fall and to incline to the vertical in response to the tendency of the element to elongate and contract and to bow on variations in the temperature conditions to which it is subjected. In this construction the changes in form of the elements C resulting from variations in their temperatures are mainly accommodated by the flexure of the upper end connections D, but the 70 sectional supports for the lower end connections D provide sufficient flexibility to avoid objectionable strains from such stresses as are created by the thermal elongation and contraction of the lower header EB. These 75 desirable results are obtained moreover with a relatively simple combustion chamber wall construction and with a minimum tendency to leakage through that wall. While as previously explained, the repeated heating and 80 cooling to which the elements C of Figs. 10, 11, and 12 are exposed will eventually result in the bending of the elements C into bow form with their concave sides toward the 85 combustion chamber X portions as shown, 100 and while this deformation tendency is cumulative for a period after the superheater is first put into use, a stable shape is 90 ultimately attained and in this stable condition the curvature of the short elements is 95 not excessive, and in particular is not sufficient to interfere with the effective operation 105 of the soot blowing provisions C⁶⁰.
- Aside from prevention of objectionable deformation of the elements themselves by 110 restraining their bowing tendency, there is a special advantage in preventing bending movements of the end portions of the elements because of the beneficial effect on the 115 transverse end connections. When the headers are rigidly supported, the bodily elongation and contraction of the elements C necessarily results in corresponding bending movements of the end connecting nipples or 120 tubes D. The tendency of such bending movements to work the nipples D loose from the elements and the headers is materially 125 augmented, of course, by the bending movements of the elements when the last mentioned movements are not restrained. In 130

practice this difficulty is more important with respect to the connections between the elements C and the nipples D, than between the latter and the headers, as it is more readily feasible to make a good connection between the headers and nipples D than between the latter and the elements.

The connection of the elements C closely adjacent their ends to a rigid supporting framework, as in the construction shown in Figs. 1 to 9, greatly reduces the difficulty of maintaining the strength and tightness of the joints between the nipples D and the elements. Somewhat the same advantage is secured with the construction shown in Figs. 10, 11, and 12 by connecting each element C at each end, and particularly at its upper end, to the corresponding ends of the other elements as by means of an angle bar F³⁰ connected to the elements closely adjacent the nipples D, by bolting them to lugs C¹¹ formed on the backs of the elements. The advantage of thus connecting the elements C together adjacent their ends is, largely due to the fact that in practical operation the various elements are not all subjected to the same bowing tendency at the same time. In consequence, the distortion of an element in which the bowing tendency is relatively large, is restricted by its connection to the elements in which the bowing tendency is relatively small. In practice, the use of the bars F³⁰, and particularly of the upper bar F³⁰, makes it practically possible in some cases to use rigidly mounted headers, where otherwise headers mounted on yielding supports would be required.

Certain features of construction and arrangement pertaining to a furnace wall superheater having furnace wall lining elements with flexible transverse end connections extending through the furnace wall, and pertaining to the combination of furnace wall lining superheater elements with a rigid metallic supporting framework not claimed herein, but disclosed in common herein and in my prior application Serial No. 607,781, filed December 19, 1922, are claimed in said prior application.

While in accordance with the provisions of the statutes, I have illustrated and described the best form of my embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features.

Having now described my invention what I claim as new and desire to secure by Letters Patent, is:

1. The method of preventing objectionable

deformation of an elongated channeled element absorbing radiant heat at one side which consists in substantially restraining the tendency of the element to bend in a plane parallel to its length and transverse to its heat absorbing face while permitting the element to elongate and contract freely in response to changes in its temperature.

2. The method of preventing objectionable distortion of an elongated channeled element absorbing radiant heat at one side which consists in permitting the element freedom to expand and contract in the direction of its length while applying force to the element at points distributed along its length as required to restrain the tendency of the element to bend in a plane parallel to its length and transverse to its heat absorbing side.

3. In radiant heat absorbing fluid heating apparatus the combination with an elongated channeled element absorbing radiant heat at one side, of supporting means for said element engaging the latter at points distributed along its length and thereby holding the element against bending movements in a plane parallel to its length and transverse to its heat absorbing side while permitting a bodily elongation and contraction of the element in the direction of its length.

4. Radiant heat absorbing fluid heating apparatus comprising a plurality of elongated channeled elements arranged side by side to provide an extended heat absorbing face and a rigid supporting frame to which each of said elements is connected adjacent its ends and at one or more intermediate points in such manner as to permit the thermal elongation and contraction of each element while substantially restricting the tendency of the element to bend in a plane transverse to said frame.

5. In radiant heat absorbing fluid heating apparatus the combination with a plurality of elongated channeled elements arranged side by side, of a rigid supporting frame to which said elements are connected adjacent their ends and at one or more intermediate points by means permitting the thermal elongation and contraction of the elements but preventing movement of the elements at their points of attachment to the frame toward and away from the latter.

6. In radiant heat absorbing fluid heating apparatus the combination with a plurality of elongated channeled elements arranged side by side, of a rigid supporting frame to which said elements are connected adjacent their ends and at one or more intermediate points by means permitting the thermal elongation and contraction of the elements but preventing movement of the elements at their points of attachment to the frame toward and away from the latter, said frame

comprising structural members parallel to said elements and of a collective longitudinal stiffness sufficient to resist without appreciable flexure the stresses which are created in the elements as their temperatures vary and which tend to bend the elements in planes parallel to their length and transverse to the frame as a whole.

7. In radiant heat absorbing fluid heating apparatus the combination with a plurality of elongated channeled elements arranged side by side, of a rigid supporting frame to which said elements are connected adjacent their ends and at one or more intermediate points by means permitting the thermal elongation and contraction of the elements but preventing movement of the elements at their points of attachment to the frame toward and away from the latter, said frame comprising structural members parallel to said elements and of a collective longitudinal stiffness sufficient to resist without appreciable flexure the stresses which are created in the elements as their temperatures vary and which tend to bend the elements in planes parallel to their length and transverse to the frame as a whole and structural members transverse to the first mentioned members through which the latter are connected to said elements.

8. The combination with radiant heat absorbing fluid heating apparatus comprising elongated heat absorbing elements and transverse end connections to said elements, of a furnace wall having metallic parts incorporated therein to form channels through which said end connections extend and in which they are loosely received, and heat insulating material packed in said channels about the end connections to restrict air leakage through the channels while permitting movements of the end connections resulting from the thermal expansion and contraction of the elements.

9. The combination with a radiant heat absorbing fluid heating apparatus comprising elongated heat absorbing elements and a transverse end connection to one end of each element, of a furnace wall formed with channels through which said end connections are loosely passed and at the inner side of which said elements are disposed, a header at the opposite side of the wall to which one end of each transverse connection is connected, means incorporated in the wall to which each of said elements is anchored at a distance from its said end connection, and a support for said header adapted to yield to accommodate the thermal elongation and contraction of said elements.

10. The combination with a radiant heat

absorbing fluid heating apparatus comprising elongated heat absorbing elements and transverse end connections to said elements, of a furnace wall having metallic parts incorporated therein to form channels through which said end connections extend and in which they are loosely received, and heat insulating material packed in said channels about the end connections to restrict air leakage through the channels while permitting movements of the end connections resulting from the thermal expansion and contraction of the elements and covers secured to said end connections and closing the outer ends of said channels.

11. In radiant heat absorbing fluid heating apparatus the combination with a plurality of elongated channeled heat absorbing elements and transverse end connections to said elements, of a combustion chamber wall at one side of which said elements are disposed, a rigid metallic frame incorporated in said wall and metallic portions at the opposite sides of said frame providing channels through which said end connections extend through the wall and means anchoring said elements to said frame.

12. A radiant heat absorbing fluid heating apparatus the combination with elongated channeled elements provided with transverse end connections, of a furnace wall at one side of which said elements are arranged and which is formed with channels through which said connections extend and in which they are loosely received, an anchorage to which said elements are connected at a distance from said end connections, a packing of heat insulating material in said channels about said end connections adapted to yield to accommodate movements of said end connections resulting from the thermal expansion and contraction of the elements, and covers secured to said end connections for preventing the escape of said material through the outer ends of said channels.

13. In radiant heat absorbing fluid heating apparatus comprising a row of elongated channelled elements each absorbing radiant heat at one side, transverse connections to the ends of the elements for passing the fluid to be heated through the channels in the elements, of a support to which each element is connected adjacent one end whereby the tendency to unequal movements of the different elements in response to temperature changes is restricted.

Signed at New York city, in the county of New York and State of New York, this 16th day of July A. D. 1924.

JOHN E. BELL.
